(57) **CLAIM**

The ornamental design for an electrical power unit for a work surface, as shown and described.

DESCRIPTION

FIG. 1 is a front perspective view of an electrical power unit for a work surface in an open configuration showing our new design;

FIG. 2 is a rear perspective view thereof;

FIG. 3 is a front elevation thereof;

FIG. 4 is a rear elevation thereof;

FIG. 5 is a top plan view thereof;

FIG. 6 is a bottom plan view thereof;

FIG. 7 is a left side elevation thereof; and,

FIG. 8 is a right side elevation thereof.

In the drawings, the broken lines are for the purpose of illustrating environment only and form no part of the claimed design.
